UNITED STATES PATENT OFFICE.

WILLIAM L. R. EMMET, OF SCHENECTADY, NEW YORK, ASSIGNOR TO GENERAL ELECTRIC COMPANY, A CORPORATION OF NEW YORK.

BOILER.

1,194,157.

Specification of Letters Patent.

Patented Aug. 8, 1916.

Application filed December 12, 1912, Serial No. 736,323. Renewed December 3, 1915. Serial No. 64,937.

To all whom it may concern:

Be it known that I, WILLIAM L. R. EMMET, a citizen of the United States, residing at Schenectady, county of Schenectady, State of New York, have invented certain new and useful Improvements in Boilers, of which the following is a specification.

My invention relates to means by which mercury can be effectively vaporized for use in a turbine within the temperature ranges to which it is economically adapted. The efficiency of processes by which power is generated by the expansion of vaporized liquids depends upon the range of temperature through which the vapor can act in a saturated condition, and it is with a view to extending the range available with steam that the use of mercury is proposed, the purpose being to work the mercury through a temperature range above that conveniently available with steam and to condense the mercury vapor in a steam boiler so that the heat delivered may be used as it now is in an ordinary condensing or non-condensing steam process.

Mercury vaporizes at atmospheric pressure with a temperature of 677° F. and condenses in a vacuum of 28" at about 457° F. Since leakage of mercury would involve loss and other difficulties, it is desirable to vaporize the mercury at a low pressure, preferably slightly below that of the atmosphere, and from the figures above given, it may be seen that a temperature range of over 200° F. is available without exceeding atmospheric pressure or going below a convenient degree of vacuum and that the temperature of condensation is still above that generally used in steam processes.

With a boiler suited to the effective vaporization of mercury without the use of an excessive quantity of the liquid, the process of turning heat into power is relatively simple since the high vapor density of the mercury and relatively low power per pound of material gives a low jet velocity which is conveniently applicable to drive a turbine of very simple construction. By placing the mercury turbine and steam boiler slightly above the level of the mercury boiler, the condensed fluid can be drained back by gravity so that no pumps will be required and so that the system is completely closed except for the packings on the mercury turbine shaft, which packings can be

effectively sealed to prevent the loss of mercury.

The volume of mercury vapor required in the process above described is many times as great as that of the steam and this fact, combined with the high cost of mercury, makes necessary a boiler construction very different from that used with steam. In storage space steam boilers, that is, boilers having a space in which steam is stored, the liquid generally covers the heating surface and the vapor rises as bubbles through the liquid or accompanies a stream of the liquid induced by ebullition which constantly wets the heating surface and withdraws heat from it. In producing so large a volume of vapor as is required in the mercury boiler, very ample space for the circulation of liquid would have to be provided if an action similar to that of the steam boiler was sought, and to fill such a space with liquid mercury would involve a prohibitive cost. I therefore have devised another means of removal of heat from the interior walls of the surface to be heated by the furnace.

It has been found that when a gas is moved in contact with a heated surface, the rate of heat removal from the surface by the gas greatly increases with velocity of movement, and data obtained by movement of air on heated surfaces show that with reasonable velocities an adequate rate of removal can be maintained by the mercury vapor in contact with the heating surface without incurring serious pressure differences. If, however, vapor alone moved in contact with any part of the heating surface, it would superheat, and while it would again saturate on coming in contact with the liquid, this action would involve higher temperatures of the heating surface and lower efficiency. If, however, the conditions are such that the vapor moving in contact with the heating surface is accompanied by a sufficient amount of liquid in a finely divided state, this liquid will itself take up heat from the heating surface and will, by vaporization, absorb the heat which is taken up by the moving vapor. Such a combined action of the liquid and vapor is accomplished by the design of boiler here shown and described.

In the accompanying drawings which are illustrative of my invention, Figure 1 is a longitudinal section of my improved boiler;

Fig. 2 is an enlarged sectional view of the boiler; Fig. 3 is an enlarged detail view of two of the tubes; Fig. 4 is a detail view of a slight modification of the tube structure; Fig. 5 is a sectional detail view of a heater for heating the mercury prior to its introduction into the boiler proper; Fig. 6 shows a modified construction of the cores for the heater; and Fig. 7 a modified construction 10 of the cores for the boiler.

6 indicates a metal shell of any suitable construction containing the boiler tubes 7 and provided with a suitable heating means. As shown a grate 8 is arranged in the front 15 of the shell to support a coal fire in the ordinary manner. The rear end of the shell is extended to receive the heater 9 which in effect forms a part of the boiler. This is subjected to the flue gases after they have 20 passed between the boiler tubes and given up heat thereto. The gases are collected in a hood 10 at the end of the shell and from said hood they pass by the conduit 11 to the chimney 12. In the conduit I may insert a 25 feed water heater 11^a for a steam boiler. Thus the heat of the flue gases is absorbed first by the boiler and then by the heater and economizer, said gases flowing through them in series.

30 The shell is provided with a tube sheet 12^a in which the tubes 7 are supported in a vertical or substantially vertical position as will appear more fully hereinafter. Above said sheet is a vapor chamber 13 communicating by the pipe 14 with a mercury vapor turbine. The heater 9 is composed of vertical tubes 15 that are supported between heads 16 and 17 as will appear later. Mercury in liquid form is fed to the heater by 35 gravity from the pipe 18, the latter being connected at its other end to the mercury vapor condenser of the turbine driven by the vapor generated in the boiler. In this pipe is a trap 19 the legs of which should be 40 at least thirty inches long to act as a seal to prevent the boiler from forcing mercury or vapor upward through the pipe 18, it being remembered that the boiler is working under atmospheric pressure or a pressure 45 slightly below it. To the left-hand end of the heater is connected a pipe 20 to convey heated mercury therefrom to the hottest end of the boiler. The boiler end of the pipe opens into the vapor chamber 13 and the 50 mercury flowing therefrom is free to flow over the tube sheet 12^a and run into the tubes.

Referring to Figs. 2 and 3, 7 indicates the vertically disposed tubes which are closed 55 at their lower ends and at their upper ends are expanded or otherwise secured to the tube sheet 12^a. Inside of each tube is a core 21 of clay, hydraulic cement or other cheap material which is heat resisting to a greater 60 or less degree. The periphery and lower

end of each core is provided with projections 22 which serve to center it within the tube and also to afford an annular vertical vaporizing space 23 of small cross-section and large area exposed to the hot tube and a 70 small transverse connecting passage or space 24. The upper end of the core is provided with a V-shaped opening 25 forming a cup to receive mercury from the chamber on the upper side of the tube sheet. The center of 75 the core is provided with a passage 25^a through which mercury in liquid form is fed by gravity to the annular vertical space 23. The cores are held in place by clamps 26 that are secured by screws or bolts 27 or 80 equivalent means. Each clamp has down-turned ends engaging the V-shaped openings in two adjacent cores so that one clamp suffices for both. Instead of using a number of small projections the cores may be provided with spiral ribs 22^a as shown in Fig. 7 which perform the same office. Being 85 thin they do not appreciably cut up the annular vaporizing spaces 23.

In Fig. 4 is shown a slight modification 90 of the core structure. 28 indicates a tubular envelop or casing made of some metal unaffected by mercury in which the core is located. The core may with advantage be inserted in the envelop in a plastic condition 95 and afterward permitted to harden. The ends of the envelop are closed by heads or caps 29. The envelop and lower head are provided with projections 22 that serve to center the core and form the spaces 23 and 100 24 previously referred to. This arrangement while somewhat more expensive to construct has the advantage of greater accuracy so that the central passage and outer space can be made to strictly conform to the 105 requirements. The cores are held in place by clamps 26 as before.

The action of the boiler is as follows: The supply of mercury in the system is approximately enough to fill all the annular spaces 110 23 and the central passages 25^a together with the cups at their upper ends. When no heat is applied the mercury will fill all these passages by gravity, the tube sheet 12^a being placed in a horizontal position. When heat 115 is applied a part of the mercury in the annular spaces surrounding the cores will be vaporized, which vapor with the liquid that accompanies it will be forced up into the vapor chamber 13, the rapidity of this action 120 depending upon the amount of heat supplied by the fire. The liquid accompanying the discharge of vapor being thrown upward into the chamber will fall back and be caught in the cups 25 from which it will be 125 forced by gravity down the central passages 25^a into contact with the heated walls of the tubes. Thus a constant circulation of mercury in the presence of its vapor is maintained in contact with the heating surfaces 130

and the velocity of this circulation will increase with increased delivery of heat. Increased velocity results in more effective heat removal by the vapor and thus affords 5 heat transference from the heated walls to the liquid which is to be vaporized. By making the vaporizing spaces of small cross-section and large heating surface this action is greatly facilitated.

10 Referring to Fig. 5, 16 and 17 indicate the top and bottom plates of the heater, said plates being suitably supported within the boiler shell. Between the plates and suitably secured are vertically disposed tubes 15 which are open at both ends. These tubes need not be strictly vertical. The main thing is to so arrange them that mercury can be fed thereto by gravity. Inside of each tube is a core 30 made of clay or hydraulic 20 cement which is provided with peripheral projections 31 that serve to center it and form an annular space 32 for the mercury to be heated prior to its entrance into the boiler proper. The end of each core is provided with one or more projections 33 to support the core and provide a space for the 25 mercury. The tubes may and usually would be arranged in sets through which the mercury flows in series, the tubes of each set being 30 connected in multiple as regards the passage of mercury. The right-hand tube receives mercury from the opening 34 communicating with the chamber 35 which receives mercury from the trap 19 previously 35 referred to. It flows downwardly through the annular space in each tube of the first set to the connecting passage 36 at the bottom from which it flows upwardly through the annular passages of the second set to the top 40 connecting passage 37. From this passage the mercury flows downwardly through the third set of tubes and so on. By reason of this arrangement the mercury will pick up a large amount of heat in its passage to the 45 boiler. This action is facilitated by the fact that the annular passages 32 are relatively thin, measured in a plane perpendicular to the core, and the heating surface of the tubes relatively large being similar in this 50 respect to the boiler tubes. The passages should however be large enough to admit free flow of the fluid without excessive friction. The mercury after being thoroughly 55 heated enters the chamber 38 from which it flows by the pipe 20 to the boiler proper as hereinbefore explained. As arranged the liquid enters the heater at the end remote from the fire where the gases are coolest and flows toward the fire where the gases 60 are hotter. In other words, the coolest liquid is acted upon by the coolest gases.

In Fig. 6 is shown a slight modification of the heater wherein the cores for the tubes are mounted in thin metal envelopes 39 similar in construction to those referred to in

connection with Fig. 4 and for the same purpose. They are also provided with metal ends or covers 40. Normally the heater and also the trap feeding it will be filled with mercury.

I am of course aware of the so-called capillary boilers for water in which the tubes or passages are largely filled with some material to hold the water in boiling contact with the walls of said tubes or passages but the vaporizing spaces in my improved boiler are in no sense "capillary" in their nature. In such boilers water has to be forced under relatively high pressure by a pump through the passages whereas in my case the feeding of liquid to the vaporizing spaces is solely by gravity. Further such boilers do not have the feeding passages in the core as herein specified nor the storage space for vapor and liquid.

I have not described the power system to which my improved boiler is especially adapted because it forms the subject matter of my application for Letters Patent, Serial No. 63,992 filed November 29, 1915.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is—

1. A boiler for vaporizing liquids, comprising a plurality of heating tubes, and a core for each tube formed of a material which is a poor conductor of heat and which is of but slightly less diameter than said tube whereby a narrow annular space is formed between the outer surface of the core and the inner surface of the tube, said core having a relatively small axial opening.

2. A boiler for vaporizing liquids, comprising a plurality of heating tubes, a core for each tube formed of a material which is a poor conductor of heat and which is of relatively large diameter, whereby but a narrow space is formed between the outer surface of the core and the inner surface of the tube, and means for spacing each core relative to its tube, each core being provided with a relatively small axial opening communicating at one end with the space and having a cup-shaped opening at the other for feeding liquid by gravity thereto.

3. A boiler for vaporizing liquids, comprising a vapor chamber, a plurality of heating tubes depending from and communicating at one end with said chamber and closed at the other end, a core for each tube formed of a material which is a poor conductor of heat and which is of but slightly less diameter than the tube whereby a com-

paratively narrow annular space is formed between the outer surface of the core and the inner surface of the tube, said core having a relatively small axial opening communicating at one end with said chamber and at the other with the space between the core and the tube.

4. A boiler for vaporizing liquids comprising heating tubes, thin tubular metal envelopes located in the tubes and separated therefrom by clearance spaces, a filling of

relatively non-heat conducting material for the envelops, each of said envelops and its filling being provided with a longitudinally extending passage that communicates with 13 the space between the envelop and its tube.

In witness whereof, I have hereunto set my hand this 11th day of December, 1912.

WILLIAM L. R. EMMET.
